UNITED STATES PATENT OFFICE.

ABRAHAM M. MALOUF AND FRED M. MALOUF, OF BROOKLYN, NEW YORK.

GARTER.

Application filed June 27, 1921. Serial No. 480,582.

To all whom it may concern:

Be it known that we, ABRAHAM M. MALOUF and FRED M. MALOUF, citizens of the United States, residing at Brooklyn, in the county of Kings, State of New York, have invented a new and useful Garter, of which the following is a specification.

The device forming the subject matter of this application is a garter, and one object 10 of the invention is so to construct the garter that the rigid parts thereof will not engage the body of the wearer. Another object is to place the strain on the bend of the loop which carries the rider wherewith the keeper engages. A further object is so to dispose the strap of the garter that the main 15 loop, which carries the rider, is prolonged to form an auxiliary loop, which supports the keeper, the end of the auxiliary loop being housed, and it being possible so to stitch the strap as to form both loops readily.

In the drawings, Figure 1 is an elevation of the complete garter; Figure 2 is a longitudinal section; Figure 3 is a plan showing 25 the keeper; Figure 4 is a plan showing the rider.

The device embodies a loop-shaped keeper 1 having an eye 2, and a rider 3 having openings 4, the keeper and the rider being formed of metal or some other rigid material. The rider 3 has a stud 15 carrying a button 16 generally made of rubber. A flexible strap 5 is provided and ordinarily is inelastic, the strap being formed into a main loop 6 comprising an inner member 7 and an outer member 8, the outer member 8 being extended to form the outer member 10 of a depending auxiliary loop 9, the inner member 11 of which is located 30 between the outer member 10 of the loop 9 and the outer member 8 of the loop 6, the inner member 11 of the loop 9 being continued to fashion a depending tongue 12, the members 7, 8, 10 and 11, and the tongue 12, being connected in any suitable way, for 40 instance by stitching 14.

The outer member 8 of the loop 6 passes through the openings 4 of the rider 3 and the rider rests in the lower end of the loop 6 when the button 16 is engaged with the keeper 1. Thus, the strain is so placed that 50 the stitching 14 will not be torn away. The inner member 7 of the loop 6 prevents the rider 3 from coming into contact with the body of the wearer, and both the member 11 and the member 10 exercise a like function with respect to the keeper 1.

Owing to the way in which the loops 9 and 6 are formed, and owing to the presence of the tongue 12, the strap 5 does not 55 present a ragged end and the stitching 14 has a secure hold.

What is claimed is:

1. A device of the class described comprising a strap fashioned into a main loop including an inner member and an outer 65 member, the outer member being extended to form the outer member of an auxiliary loop, the inner member of which is located between the outer members of the loops; means for uniting the members of the loops 70 to close them at one end; a keeper supported in the other end of the auxiliary loop; and a rider slideable upon the outer member of the main loop and cooperating with the keeper, the rider being supported in the 75 other end of the main loop.

2. A device of the class described, constructed as set forth in claim 1 and further characterized by the fact that the inner member of the auxiliary loop is extended 80 to form a tongue, located between the inner member of the auxiliary loop and the outer member of the main loop, and engaged by said means.

In testimony that we claim the foregoing 85 as our own, we have hereto affixed our signatures.

ABRAHAM M. MALOUF.
FRED M. MALOUF.
